UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL CASTING MACHINE.

Application filed July 11, 1924. Serial No. 725,343.

This invention relates to typographical casting machines, such as linotype machines of the general organization represented in U. S. Letters Patent No. 436,532, wherein molten metal is pumped at intervals from a melting pot into a mold up against a composed line of matrices for the production of printing bars or slugs. In order to secure the most advantageous results, it is desirable that the molten metal in the pot be kept as nearly as possible at a constant level and at a substantially uniform temperature. The present invention obtains these results by the provision of an automatic feeder which supplies cold metal to the pot at such times and in such quantities as may be required.

In the preferred embodiment illustrated, the cold metal is in the form of long bars or pigs, provided along one of their faces with a series of arresting teeth or shoulders, and is fed into the pot by gravity through a guide or chute under the control of an automatic pawl or detent which cooperates with the teeth on the bars to effect the progressive step-by-step advance of the bars along the guide. A power device or lever, operated by some moving part of the machine, (e. g., by the melting pot itself) actuates the pawl at predetermined periods to cause the feeding of the metal bars, and means, (such as a float) governed by the level of the molten metal in the pot, control the period of actuation of the pawl. The construction of the parts and their mode of operation will best be understood from the detailed description to follow.

In the accompanying drawings:

Fig. 1 is a side elevation, partly in section, of the melting pot of a linotype machine equipped with the improved automatic feeder;

Fig. 2 is a vertical section taken through the guide or chute and showing one of the metal bars in cooperation with the automatic feed pawl;

Fig. 3 is a cross-section taken on the line 3—3 of Fig. 2;

Fig. 4 is a similar view, but showing the pawl withdrawn from the guide to release the metal bar;

Fig. 5 is a detached perspective view of the guide and the parts mounted thereon; and

Fig. 6 is a view similar to Fig. 2, on a greatly reduced scale, showing both ends of

the metal bar, and the manner in which it is allowed to follow the preceding one through the guide.

For the sake of clearness, only such parts of a linotype machine as are immediately concerned with the present invention have been shown in the drawings. As illustrated in Fig. 1, the melting pot A is provided with the customary delivery throat or mouth A¹ through which the molten metal is injected by the pump B into the mold C for the slug casting operation. As is well known, at each cycle of operation of the machine, the pot A is swung to and from the mold by the rotary cam D, Fig. 1 showing the pot in its forward or casting position.

In carrying out the present invention, the cold metal to be supplied to the pot is in the form of long bars or pigs X, which may be of any suitable length and of any desired from in cross-section, and which are provided with a series of squared-off arresting teeth or shoulders X¹. In the example illustrated, the teeth are cast on one of the side faces of the bars and extend entirely across the same from one edge to the other, the rear walls X² of the intermediate recesses sloping upwardly toward the shoulders to facilitate their cooperation with the feed pawl. The metal bars X are fed into the pot through a suitable guide or chute E extended downwardly through an opening in the pot cover. As a convenient means of support, the chute is provided at its opposite edges with horizontal ribs or ledges E¹ and vertical tongues E², the latter being fitted in slots formed in the opposing faces of a pair of upright supports A² on the pot cover, and the former resting upon the upper edges of said supports. As thus supported, the chute E and all of its attached parts may be readily applied to and removed from the pot at will. The chute is provided with a pair of grip handles E³ to facilitate such manipulation.

The feeding of the metal bars through the chute E is controlled by a pawl or detent F pivoted by a pin F¹ to the side of the chute and adapted to be rocked into and out of engagement with the metal bars through an aperture E⁴ cut through the side of the chute. As shown in Fig. 2, when the pawl F is in active position, it stands in engagement with one of the shoulders X¹ and positively prevents the descent of the bar.

When, however, the pawl is withdrawn or moved to inactive position (Fig. 4), it clears the shoulders X^1 and permits the bar to slide downwardly along the chute. In this connection, it may be noted that the chute is provided at its lower end with a steel strap or stirrup E^5 which limits the descent of the metal bar when released by the pawl. After the metal bar has thus been released, 10 the pawl F is returned to active position in time to be engaged by the following shoulder X^1 and again limit the descent of the bar until the time arrives for the next release of the bar. In this way, the pawl, and particularly in cooperation with the strap E^5 , exercises a positive control over the metal bar and insures its progressive step-by-step advance into the pot under the action of gravity.

20 Directly above the pawl F and mounted to turn on the same pivot pin F^1 , is a right-angled actuating lever G , the shorter arm of which is formed with a depending lip G^1 arranged to engage the outer edge of the pawl F . A helical spring H , connected at one end to the longer arm of the actuating lever G and at its opposite end to the side of the chute E , tends constantly to hold the lip G^1 in engagement with the pawl F and the latter in active position, or in engagement with the metal bar. When the melting pot A is swung forward to casting position, the longer arm of the actuating lever G engages an upright pin J^1 of a stationary bracket J and is rocked rearwardly on the pivot F^1 against the action of the spring H (see Figs. 1, 3 and 4).

So long as the molten metal in the pot is at the desired level, the rocking movements 40 of the actuating lever G do not affect the pawl F , which remains projected into the chute E to prevent the release or descent of the metal bar; but when the metal falls below such level, the pawl is automatically 45 coupled to the actuating lever and withdrawn from the chute so as to release the metal bar in the manner before described. Such action of the parts is controlled by a float K located in the melting pot A and resting in the molten metal. This float is connected to the lower end of a vertical rod or stem K^1 slidable in guides E^6 on the side of the chute and bent at right angles at its upper end to make telescopic connection with a sleeve K^2 carrying a vertical coupling pin K^3 . This pin K^3 passes downwardly through a tubular boss G^2 rising from the shorter arm of the actuating lever G and is adapted to be lowered into or lifted out of 55 engagement with a hole or recess F^2 formed in the pawl F according to the position of the float K .

From the foregoing, it will be seen that 60 the actuating lever G is rocked to and fro at each casting operation, being moved in

one direction by its engagement with the stationary pin J^1 as the melting pot A advances to casting position, and in the opposite direction by the spring H as the pot retreats from casting position. Such to-and-fro motions of the actuating lever are purely idle and do not affect the pawl F until the molten metal in the pot drops below the desired level. When this occurs, as above 70 intimated, the float K lowers the coupling pin K^3 into the recess F^2 of the pawl F and connects the latter to the actuating lever. Due to this connection of the parts, upon 75 the next advance of the melting pot to casting position, the pawl F is withdrawn from the chute E and becomes disengaged from the tooth X^1 on the metal bar X (see Fig. 4), permitting the latter to slide downwardly by gravity into the melting pot until 80 it is arrested by the strap E^5 . The metal bar, in entering the molten metal, displaces the same and forces the float K upwardly, thereby lifting the coupling pin K^3 out of engagement with the recess F^2 and disconnecting the pawl from the actuating lever G . Consequently, when the melting pot recedes, 85 the spring H acts instantly to rock the actuating lever G back to its original position and at the same time, due to the engagement 90 of the lip G^1 with the pawl F , to project the latter back into the chute E for engagement with the next tooth X^1 on the metal bar. The pawl F then remains in this position until it is again coupled to the actuating lever by the lowering of the float K , the foregoing operations being repeated whenever 95 the molten metal falls below the desired level. In this way, the metal bars are fed into the pot step by step under positive control and in such manner that the molten metal is kept at a substantially constant level and at a practically uniform temperature.

It may be observed that when the last or uppermost tooth on the metal bar passes the pawl F , the bar is then free to pass into the melting pot as rapidly as it is fused. This would result in a slight raising of the metal within the pot above the level desired, if the bar were of uniform bulk throughout. To avoid this result, the upper end portion 110 of the bar is preferably reduced or cut away as at X^3 (see Fig. 6), so that the continued fusion thereof will not cause the molten metal to rise excessively, the latter being thus kept at approximately the same level at all times. As an alternative, the pawl F might be placed at a lower level or nearer the lower end of the guide or chute E , if desired. It may also be observed that, by reason of the foregoing condition, a new bar when placed 115 in the chute to follow its predecessor, if formed with teeth X^1 throughout its extent, would be arrested by the engagement of the pawl F with its first or lowermost tooth, and when released, caused to drop the full dis-

tance from the pawl to the strap E⁵. While this would not be serious, it may be avoided by omitting the teeth X¹ at the lower end of the bar, as indicated in Fig. 6, which shows a new bar resting upon the remaining portion of the preceding bar. It will be apparent from this figure that as the old bar melts away, the new bar is permitted to slide down the chute until arrested by the engagement of its first tooth with the pawl F, at which time the end of the bar will stand only a short distance away from the strap E⁵.

The foregoing improvements have been shown merely in preferred form and by way of example, and as applied to a casting pot of the regular linotype machine, but obviously many modifications and alterations may be made therein and in their mode of adaptation without departing from the spirit of the invention. For instance, the form of the teeth on the metal bars may be variously modified and still made to perform their function. Again, the periodic operation of the actuating lever, instead of being effected by the motion of the melting pot, may be carried out in some other way, as for example, from some other moving part of the machine, although in any case it is preferred that the lever be operated at least once for each casting operation. Again, the connection of the feed pawl to the actuating lever may be controlled by some other means than a float, such as by a thermostat located in the pot, the essential idea in this connection being that the connection of the parts should be controlled by the level of the molten metal. These and various other changes will readily suggest themselves to those skilled in the art. It should be understood, therefore, that the invention is not limited to any specific form or embodiment, except in so far as such limitations are specified in the claims. It may be noted, however, that the particular arrangement shown and described is extremely simple, compact, and requires only a few parts, which cooperate in a very effective manner to carry out the objects of the invention.

Having thus described my invention, its construction and mode of operation, what I claim and desire to secure by Letters Patent of the United States, is as follows:

1. A type-metal bar feeding mechanism for the melting pot of a linotype machine, said mechanism consisting of a feed pawl movable into and out of engaging relation to the type-metal bar, a periodically actuated member for withdrawing said pawl from engagement with the bar, and an automatically controlled coupling device for connecting the periodically actuated member directly to the feed pawl or for disconnecting said parts, as required.

2. A type-metal bar feeding mechanism for the melting pot of a linotype machine, said mechanism consisting of a feed pawl movable into and out of engaging relation to the type-metal bar, a periodically actuated member for withdrawing said pawl from engagement with the bar, and a float supported coupling device for connecting the periodically actuated member directly to the feed pawl or for disconnecting said parts, according to the height of the molten metal in the pot.

3. A type-metal bar feeding mechanism for the melting pot of a linotype machine, said mechanism consisting of a pivoted feed pawl movable into and out of engaging relation to the type-metal bar, a periodically actuated lever pivoted on the same axis as the feed pawl for withdrawing it from engagement with the bar, and a float-controlled coupling pin for connecting the lever directly to the pawl or for disconnecting said parts, according to the height of the molten metal in the pot.

4. A type-metal bar feeding mechanism for the melting pot of a linotype machine, said mechanism consisting of a pivoted feed pawl movable into and out of engaging relation to the type-metal bar and formed with an aperture to receive a coupling pin, a periodically actuated lever for withdrawing the pawl from engagement with the type-metal bar and formed with a tubular boss adapted to register with the aperture in the feed pawl, and a float-controlled coupling pin slidably arranged in said tubular boss and adapted to be lowered into the aperture of the feed pawl to connect it directly to the periodically actuated lever when the molten metal in the pot drops below a predetermined level.

5. A type-metal bar feeding mechanism for the melting pot of a linotype machine, said mechanism consisting of a pivoted feed pawl movable into and out of engaging relation to the type-metal bar, a periodically actuated lever pivoted on the same axis as the feed pawl and formed with a lip portion to engage the pawl at its outer edge and move it into engaging relation to the type-metal bar, a coupling pin for connecting the lever directly to the pawl to enable the lever to withdraw the pawl from engagement with the bar, and a float carrying the coupling pin and controlling its operation according to the height of the molten metal in the pot.

6. A type-metal bar feeding mechanism as specified in claim 1 including a removable guide chute for the type-metal bar, and characterized by the fact that the feed pawl, actuating member, and coupling device are all mounted upon and carried by the guide chute, whereby the feeding mechanism may be applied to or removed from the melting pot as a unit.

7. A type-metal bar feeding mechanism for the melting pot of a linotype machine, said mechanism consisting of a type-metal bar guide chute having means to support it in an upright position within the pot, and an automatically controlled feed pawl movable into and out of engaging relation to the

type-metal bar, said pawl being located at such distance above the lower end of the chute as to stand outside of the melting pot, ¹⁰ as and for the purpose described.

In testimony whereof I have affixed my signature hereto.

DAVID S. KENNEDY.
